UNITED STATES PATENT OFFICE.

CLARENCE FIRTH, OF INDIANAPOLIS, INDIANA.

DESIGN FOR A CHINA TABLEWARE ARTICLE.

54,907.

Specification for Design.

Patented Apr. 20, 1920.

Application filed August 8, 1919. Serial No. 316,269. Term of patent 7 years.

To all whom it may concern:

Be it known that I, CLARENCE FIRTH, a citizen of the United States, residing at Indianapolis, in the county of Marion and State of Indiana, have invented a new, original, and ornamental Design for China Tableware Articles, of which the following is a specification, reference being had to the accompanying drawing forming part hereof.

In such drawing, the single figure is a fragmentary plan view of a plate, showing my new design. Such a plate is an example of the china tableware articles, including dishes of all kinds as well as plates, in which my new design is embodied.

The motif containing the conventional flower is repeated at desired intervals around the edge of the article.

I claim:

The ornamental design for a china tableware article, as shown and described.

In witness whereof, I have hereunto set my hand at Indianapolis, Indiana, this sixth day of August, A. D. one thousand nine hundred and nineteen.

CLARENCE FIRTH.
